UNITED STATES PATENT OFFICE.

WILLIAM KAZAKAWITZ, OF NEW YORK, N. Y.

FOLDING UMBRELLA.

1,293,795.

Specification of Letters Patent. Patented Feb. 11, 1919.

Application filed September 6, 1916. Serial No. 118,709.

To all whom it may concern:

Be it known that I, WILLIAM KAZAKAWITZ, a citizen of the United States, residing at New York, in the county of New York and State of New York, have invented certain new and useful Improvements in Folding Umbrellas, of which the following is a specification.

This invention relates to folding umbrellas, and more particularly to a folding umbrella of that class in which the ribs of the umbrella are jointed intermediate their ends so as to be foldable upwardly and inwardly into parallelism with the umbrella stick or staff.

One of the main objects of the invention is to provide an umbrella of the character stated which, when folded, will occupy a minimum of space and may be easily carried in a suit case, pocket, or the like. A further object is to provide an umbrella in which the ribs are moved into and out of operative position by the action of radially disposed operating rods slidably and pivotally connected to the umbrella staff. A further object is to provide an umbrella having a telescoping staff of simple construction which, when in operative position, will rigidly support the umbrella head. Further objects will appear from the detail description.

In the drawings:

Figure 1 is a side view of an umbrella embodying my invention in raised position, the head of the umbrella being shown as sectioned transversely.

Fig. 2 is a view showing the ribs of the umbrella in lowered position.

Fig. 3 is a view showing the ribs as folded upward and inward preparatory to moving the head of the umbrella into completely folded position.

Fig. 4 is a central vertical section through the umbrella staff.

Fig. 5 is a fragmentary section through the staff.

Fig. 6 is a fragmentary detail view of the joint of one of the ribs and the connection between the same and one of the toggle arms.

Fig. 7 is a detailed fragmentary sectional view through the staff and the sleeve slideable thereon showing the means for securing the sleeve in adjustment on the staff.

The umbrella staff is composed of three telescoping sections numbers 1, 2, and 3. Section 2 is slideable in the top section 1, 55 and a lower section 3 is slideable in the intermediate section 2, and is provided at its lower end with a short handle 4 secured thereto. Near its lower end, upper section 1 is provided with an inwardly directed leaf 60 spring 5 secured thereto at one end. This leaf spring projects through a slot 6 through the wall of the staff section and is provided, at its inner end, with an approximately square lug 7. This lug is adapted to 65 fit into a corresponding recess through the wall of the intermediate section 2, thus locking section 2 against longitudinal movement when in extended position. The top section 1 is provided, in its inner face, with a longitudinally extending groove 8 which terminates a short distance from the lower end of this section. This groove is positioned diametrically opposite to the spring catch 5 and is adapted to receive a stub 9 projecting 70 from section 2. The stub and groove co-operate to prevent a complete withdrawal of the section 2 from section 1, and also act to insure that the opening through section 2 will at all times be brought into register 75 with the lug 7 of spring 5. When it is desired to move section 2 into inoperative position, spring 5 is moved outward so as to disengage the lug 7 from the co-operating aperture of this section. For this purpose 80 the free end of the spring is turned upward at right angles to provide a finger grip 10. Sections 2 and 3 of the staff are secured together in the same manner as sections 1 and 2. By this construction the staff may 85 be quickly and easily extended, or may be telescoped so as to occupy very little space.

In the upper end of the top staff section 1 is secured a cylindrical plug 11. A disk 12 is secured about this plug and rests on 90 the upper end of section 1. This disk is provided with a plurality of radially disposed slots which form the usual radially extending spaced ears 13 which are centrally grooved, as at 13^a, to receive a securing wire 100 14 for pivotally securing the inner ends of the ribs to the staff.

A plurality of radially disposed ribs have their inner ends pivotally secured between

the ears 13 of the disk 12, in the usual manner. Each of these ribs is formed of two sections 15 and 16. These two sections are of equal length and are pivotally secured at 5 their adjacent ends in a U link member 17. This link member has its base bar or wall positioned beneath the sections 15 and 16 of the rib. By this construction the downward movement of the outer rib section 16 about 10 its pivotal axis is positively limited, while this rib section is free to fold upward and inward about its pivotal axis into parallelism with the upper rib section 15.

A clip 18 is secured about section 15 of 15 the rib, a short distance from the link 17. This clip is pivotally secured to the outer end of an arm 19 the inner end of which is pivoted in a U link 20 which is inverted relatively to the link 17. The inner end of link 20 is pivoted to the upper end of an arm 21, the lower end of which is pivotally secured in a disk, similar to disk 12, carried by a collar 21' fixedly secured to the upper staff section 1. The arms 19 and 21, and the link 25, 20, coöperate to form toggle arms which are pivotally secured to the umbrella staff and to the ribs, and which have free movement radially to the staff.

A sleeve 22 is slidably mounted on the top 30 section 1 of the staff below the collar 21'. This sleeve is pivoted, near its upper end, with a notched or slotted disk having the radially projecting ears 23 between which are pivotally secured the lower ends of upwardly and outwardly inclined rods 24. The upper ends of the rods 24 are pivotally secured to the arms 19 intermediate their ends. When the sleeve 22 is raised into its uppermost position the rods 24 act to force the arms 19 outward radially thus extending the ribs 25 into operative position. When thus extended the ribs are bowed so as to arch downwardly by the action of the cover 26 secured thereto and to the upper end of 45 the staff by means of the usual cap secured on the upper end of plug 11. When the sleeve 22 is moved into its lowermost position, the rods 24 pull the arms 19 downward into parallelism with the upper section 50 of the staff. The links 20 permit this downward folding of the arms 19, as shown in Fig. 2 of the drawings. Also, the arms 19 act to force the arms 21 inward into parallelism with the section 1 of the staff, and into close proximity therewith. When the ribs 25 have been moved into inoperative position, the fabric cover 26 is relieved of tension and permits the outer sections 16 of the ribs to be folded upwardly and inwardly, as shown in Fig. 3 of the drawings.

In Fig. 3 of the drawings the various elements are shown in the position they occupy when the sleeve 22 has been moved into its lowermost position and the outer sections 60 65 of the ribs 25 folded upward, as stated. By

gripping the head of the umbrella, which may be considered as composed of the cover 26 together with the ribs and the various members for operating the same, in the hand and exerting radial pressure thereon, the rods 24 and arms 19 will be forced into parallelism with the staff, and the sections 15 and 16 of the ribs will be forced into parallelism so as to be brought closely adjacent each other and in close proximity with the staff. This produces a very compact bundle which occupies very little space. By lifting the springs 5 into inoperative position and forcing the sections of the staff into each other, the total length of the umbrella when folded will be but slightly greater than the length of the top section 1 of the staff. When thus folded the umbrella may be easily inserted into a suit case or the like, or may be even carried in the pocket, if desired.

To permit proper folding of the umbrella head, the inner sections 15 of the rib, the arms 19, and the rods 24, are all out of vertical alinement. For this purpose the outer end of arms 19 and rods 24 are bent or offset so as to permit proper operation of the same, as in Figs. 2 and 3 of the drawings.

In order to secure the umbrella in open position it is necessary to provide means for securing the sleeve 22 in adjustment on the umbrella staff. For this purpose I provide a pair of spaced lugs 27 which project outwardly from the sleeve. These lugs pivotally support a thumb latch 28 the upper end of which is turned inward at right angles to 1 provide a lug or detent 29 operative through a suitable aperture through sleeve 22. When the sleeve is in its outermost position the detent 29 is brought into register with a recess formed in the wall of the upper staff 1 section 1, and is forced into the same by a coil spring 30 confined between the lower enlarged end 31 of the latch 28 and the sleeve 22. This spring is held in position by suitable centering pins carried by the sleeve and the latch, and acts to force the detent 29 inward in the manner described. The enlargement 31 at the end of the latch provides means whereby the sleeve may be quickly and easily released from the staff so as to 1 permit folding of the umbrella.

By having the toggle arms composed of the arms 19 and 21, and the link 20, so arranged as to fold upwardly I am enabled to produce an umbrella which when folded is very short so as to be readily accommodated by a small traveling bag. Also, by arranging the links so that the toggle arms cannot fold downward all danger of the elements for moving the ribs into and out of operative position becoming entangled is eliminated.

What I claim is:

An umbrella including a staff, a plurality of ribs pivotally connected thereto, said ribs

being jointed substantially intermediate their ends to fold outwardly, a sleeve fixed to the staff, arms pivoted to said sleeve, short links pivoted to the arms, a second set of arms pivoted to the links and to the inner sections of the ribs, a second sleeve

to form bracing rods, and means for locking the second sleeve to the staff. 10

In testimony whereof I affix my signature in presence of two witnesses.

WILLIAM KAZAKAWITZ.
